DENTAL INSTRUMENT

Jack Diener, Washington, D. C.

Application December 8, 1952, Serial No. 324,746

9 Claims. (Cl. 32—46)

1

The present invention relates to dental instruments and more particularly to a hand instrument particularly suited for trimming the gingival margin.

In the preparation of a tooth for an inlay, it is necessary to bevel the margin of the tooth at the gumline, or under the gumline, this portion of the tooth being known as the gingival margin. The gingival margin must be beveled to allow a greater seal at this portion of the restoration, to compensate for the gold shrinkage, and to allow a better finish to the restoration.

Heretofore, using conventional gingival marginal trimmers, there is a great deal of slipping caused by the shape of the trimmers, resulting in the cutting edge slipping from the tooth into the gum causing trauma, and poor preparations due to the loss of vision caused by the resultant bleeding. Vision is poor in these areas in any case, and a sense of feel must be used. With conventional instruments for this purpose, it is almost impossible to obtain a definite width and depth to the bevel without the entire shoulder disappearing into a lay bevel.

It is therefore an object of the present invention to provide a dental instrument which may be used as a gingival marginal trimmer in such a manner that the danger of cutting into the gum is substantially reduced.

It is a further object of the present invention to provide a dental instrument which will trim the gingival margin of the tooth to yield a bevel of definite width and depth.

It is a still further object of the invention to provide an improved gingival marginal trimmer provided with a guiding surface that will permit beveling by a sense of feel without looking at the margin being worked on.

These and other objects of the invention are accomplished by providing a flat ledge along a portion of the applicator portion of the instrument to be seated on the tooth and serve as a guide for preventing slipping off of the instrument and permitting the operation of the instrument by a sense of feel.

Other objects and the nature and advantages of the instant invention will be apparent from the following description taken in conjunction with the accompanying drawings, wherein:

Fig. 1 is a side elevation of the instrument;

Fig. 2 is an enlarged detail of the applicator portion of the instrument;

Fig. 3 is an enlarged detail of the applicator portion of a modified form of the instrument;

Fig. 4 is a fragmentary view of a tooth which

2

has been partially prepared for the inlay and a portion of the instrument showing the instrument in use;

Fig. 5 is a similar fragmentary view of a tooth and a portion of a conventional instrument of the type currently in use;

Fig. 6 is a similar fragmentary view of a tooth showing the bevel obtained by use of the present invention; and

Fig. 7 is a similar fragmentary view of a tooth showing the bevel obtained by use of conventional instruments of the type currently in use.

The instrument comprises a handle portion 10 which may be of cylindrical formation and may conveniently be provided with flat sides, as shown, a rounded end 11, and a tapered end portion 12. The tapered end portion 12 bends slightly at 13 to provide an angular extension 14 having a rounded bend joining it to the tapered portion 12. The angular extension 14 again is bent in an opposite direction to form a rounded heel 15 terminating in the applicator portion 16 of the instrument.

The applicator portion of the gingival marginal trimmer shown in Fig. 2 includes a cutting edge 17 and a ledge 18 which meet in an obtuse angle therebetween. The cutting edge 17 includes approximately two-thirds of the width of the applicator portion of the instrument, where- 25 as the ledge 18 includes the remaining one-third of the width of this portion. The upper end of the cutting edge 17 is rounded so as to eliminate a sharp point at the tip thereof which might irritate the tissue.

The cutting edge 17 is beveled to a sharp edge 19 and the ledge 18 is a flat surface. As illustrated in Fig. 1, the cutting edge 17 is vertical when the instrument handle 10 is held in a vertical position; however, the angle may be varied 30 as desired to obtain the angle of bevel desired in the tooth.

In use, the flat ledge portion 18 is maintained in a horizontal position as shown in Fig. 4, resting on the flat surface 20 of the tooth. This 35 positioning of the ledge portion 18 results in the cutting edge being placed on the margin in its proper cutting position. The dentist is thus able to feel the actual margin of the tooth in the notch-like portion of the instrument without 40 watching it.

By maintaining the instrument steadily against the corner of the gingival margin and manipulating it, the cutting edge cuts the desired bevel similar to that shown in Fig. 6 with the ledge 50 acting as a guide for the cutting edge.

Utilizing this instrument, a stability of control is allowed that results in a bevel of predetermined width and depth. Utilizing the instruments in current usage, no stability is allowed to the instruments and the resulting bevel is usually very uneven, or in some cases the whole shoulder disappears into a lay bevel, as is shown in Fig. 7. This is not a desirable bevel.

Finally, slippage from the tooth into the gum is eliminated by use of this invention, thus eliminating bleeding and damage.

It should be understood that this invention applies equally well to other types of working surfaces than the cutting edge shown that are used in gingival marginal preparation, as well as to other instruments with a similar cutting edge which could utilize a ledge for control purposes. A filing surface useful in gingival marginal preparation utilizing the present invention is shown in Fig. 3.

It should be further understood that any type of handle can be substituted for the handle illustrated, and the angle between the applicator portion of the instrument and the handle can be varied as required. It is further contemplated that both ends of the handle can be supplied with applicator portions.

It will be obvious to those skilled in the art that various changes may be made without departing from the spirit of the invention and the invention is not limited to what is shown in the drawings and described in the specification, but only as indicated in the appended claims.

What is claimed is:

1. A dental instrument, comprising a handle, and an applicator portion projecting therefrom, said applicator portion having a flat ledge thereon and a working surface adjacent to said ledge, wherein said working surface and said ledge meet in an obtuse angle, whereby said ledge acts as a guide during the use of said working surface.

2. A dental instrument in accordance with claim 1, wherein said working surface includes more than one-half of the width of said applicator portion.

3. A dental instrument, comprising a handle, and an applicator portion projecting therefrom, said applicator portion having a flat ledge thereon and a working surface adjacent to said ledge, wherein said working surface includes more than one-half of the width of said applicator portion, whereby said ledge acts as a guide during the use of said working surface.

4. A dental instrument, comprising a handle, and an applicator portion projecting therefrom, said applicator portion having a cutting edge and a flat ledge thereon, wherein said cutting edge and said ledge meet in an obtuse angle, whereby said ledge acts as a guide during the use of said cutting edge.

5. A dental instrument in accordance with claim 4, wherein said cutting edge is a beveled surface.

6. A dental instrument in accordance with claim 4, wherein said cutting edge includes more than one-half of the width of said applicator portion.

7. A dental instrument, comprising a handle, and an applicator portion projecting therefrom, said applicator portion having a cutting edge and a flat ledge thereon, wherein said cutting edge is a beveled surface, whereby said ledge acts as a guide during the use of said cutting edge.

8. A dental instrument in accordance with claim 7, wherein said cutting edge and said ledge meet in an obtuse angle.

9. A dental instrument comprising a handle, and an applicator portion projecting therefrom, said applicator portion having a flat ledge thereon and a filing surface adjacent to said ledge, wherein said filing surface and said ledge meet in an obtuse angle, whereby said ledge acts as a guide during the use of said filing surface.
